CLAIM

The ornamental design for a cigar cutter, as shown and described.

DESCRIPTION

FIG. 1 is a side elevation view of a cigar cutter showing our new design in an closed position;

FIG. 2 is a side elevation view thereof in a open position;

FIG. 3 is a front elevation view thereof;

FIG. 4 is a rear elevation view thereof; and,

FIG. 5 is a top plan view thereof.

The side of the cigar cutter opposite to the side view shown in FIGS. 1 and 2 is a mirror image of that side view shown. The bottom of the cigar cutter opposite to the top view shown in FIG. 5 is a mirror image to that top view shown except that the bottom is continuous (i.e., without gaps).
